UNITED STATES PATENT OFFICE.

EDWIN B. STIMPSON, OF BROOKLYN, NEW YORK.

STRAP.

SPECIFICATION forming part of Letters Patent No. 447,917, dated March 10, 1891.

Application filed November 10, 1888. Serial No. 290,497. (No model.)

To all whom it may concern:

Be it known that I, EDWIN B. STIMPSON, of Brooklyn, in the county of Kings and State of New York, have invented a new and useful Improvement in Straps, of which the following is a specification, reference being had to the accompanying drawings.

I will describe in detail a strap embodying my improvement, and then point out the novel features in the claim.

In the accompanying drawings, Figure 1 is a face or side view of a strap embodying my improvement. Fig. 2 is a partial edge view of the same. Fig. 3 is a partial face or side view representing the lining as stopping before it reaches the end of the tab, and Fig. 4 is a reverse or back view of the form shown in Fig. 3.

This strap consists of a face-piece A, a lining-piece B, and a re-enforcing facing-piece c. The face-piece A is laid upon the lining-piece B upon one side and the re-enforcing or strengthening piece c upon the opposite side, and the parts are then secured together by a row of stitching a. In the form of my invention herein shown the stitching a extends wholly about the strap, near the side edges thereof. The face portion of the strap consists of a main or body portion a' and button-hole tabs a², the whole being made in one integral piece. As shown, the tab portions a² are of somewhat greater width than the main or body portion, and in each tab portion is formed a button-hole a³. In the example of my invention shown in Fig. 1 the lining-piece B is of the same shape as the facing-piece A, and is also formed in one integral piece.

In Figs. 3 and 4 I have shown the lining-piece B as of greater width than the facing-piece and extending beyond the facing-piece at both the side edges of the latter, and have also shown it as stopping short of the tab portions a², the point where it stops being indicated by dotted lines in said figures.

The strap is intended more particularly for use with suspenders, and when in use is to be folded or bent at about midway in its length, and so turned at the point where it is folded as to present the face portion A upon the same side of both the tab portions and the portions of the strap intermediate of the fold and tabs, while the lining will be presented wholly upon the back.

The piece c serves to effectually strengthen the strap at the point where any strain is liable to occur, and the strap as a whole is very strong and durable, and at the same time very cheaply made, while it presents a neat and finished appearance.

What I claim as my invention, and desire to secure by Letters Patent, is—

A strap composed of a facing-piece having its ends terminating in the form of tabs provided with button-holes, a lining-piece secured to the facing-piece along the opposite edges thereof, and a re-enforcing facing-piece secured on the face of the tab on the opposite side of the lining from that on which the facing-piece is secured, substantially as set forth.

EDWIN B. STIMPSON.
